UNITED STATES PATENT OFFICE

98,807

DESIGN FOR A HANDLE FOR A CASKET OR ANALOGOUS ARTICLE

Raymond Larson, Chicago, Ill., assignor to Central Metallic Casket Co., Chicago, Ill., a corporation of Illinois

Application August 17, 1935, Serial No. 58,182

Term of patent 7 years

To all whom it may concern:

Be it known that I, Raymond Larson, a citizen of the United States, residing at 2207 North Lamon Avenue, Chicago, in the county of Cook and State of Illinois, have invented a new, original, and ornamental Design for a Handle for a Casket or Analogous Article, of which the following is a specification, reference being had to the accompanying drawing, forming part thereof.

Figs. 1 and 2 are, respectively, a front eleva-

tion and a top plan view of a handle for a casket or analogous article, showing my new design, the ornamentation of the portion illustrated in dotted lines being the same as that of the part disclosed in solid lines, and

Fig. 3 is an end elevational view thereof.

I claim:

The ornamental design for a handle for a casket or analogous article as shown and described.

RAYMOND LARSON.
